UNITED STATES PATENT OFFICE.

CHRISTIAN H. T. HAGELSTEIN, OF BOSTON, MASSACHUSETTS, ASSIGNOR TO THE REECE
BUTTON HOLE MACHINE COMPANY, OF BOSTON, MASSACHUSETTS, A CORPORATION
OF MAINE.

BUTTON-ATTACHING MACHINE.

1,329,399.

Specification of Letters Patent.

Patented Feb. 3, 1920.

Application filed July 20, 1918. Serial No. 245,804.

To all whom it may concern:

Be it known that I, CHRISTIAN H. T. HAGELSTEIN, a citizen of the United States, residing at Boston, county of Suffolk, State 5 of Massachusetts, have invented an Improvement in Button-Attaching Machines, of which the following description in connection with the accompanying drawing, is a specification, like characters on the drawing representing like parts.

This invention relates to machines of the type shown in U. S. Letters Patents 1,063,885, dated June 3, 1913, and 1,099,254, dated June 9, 1914, which are constructed to 15 attach shoe buttons to shoe tops or other material.

These machines comprise button-sewing mechanism and a chute or race-way arranged to deliver the buttons singly to the button-sewing mechanism with the eye or shank of the button in proper position to receive the needle of the sewing mechanism. The construction shown in the above mentioned patents is designed to operate with shoe buttons 20 having a flat under face. It is sometimes desirable to utilize shoe buttons which are provided with a central projection or protuberance on the under face, and the object of the present invention is to provide 25 an improved form of chute or race-way which will permit the use of buttons of either style, that is, buttons which have a flat under face or buttons which have a protuberance or projection formed on the under face.

In order to give an understanding of my invention I have illustrated in the drawings a selected embodiment thereof which will now be described, after which the novel features, will be pointed out in the appended 30 claim.

Figure 1 shows a portion of a button-sewing machine embodying my invention.

Fig. 2 is an enlarged sectional view on the 45 line 2—2, Fig. 1.

Fig. 3 is a section on the line 3—3, Fig. 2.

Fig. 4 is a section on the line 4—4, Fig. 2.

Fig. 5 is a section on the line 5—5, Fig. 2.

Fig. 6 is a view of a shoe button.

50 Inasmuch as the present invention relates solely to the chute or race-way, I have not deemed it necessary to illustrate in the drawings a complete button-sewing machine. I have, however, shown at 1 a portion of the head of the machine in which reciprocates

the needle-bar 2 forming part of the button-sewing mechanism, and I have also shown at 3 a portion of the button-containing hopper, and at 4 I have shown the chute or race-way through which the buttons are delivered 50 to button-attaching position, in which position they are acted upon by the button-sewing mechanism. The chute or race-way is provided with a stud 5, which is pivoted in a bearing 6 formed on the head 1, suitable 55 means being provided to oscillate the chute and hopper in timed relation with the movements of the button-sewing mechanism all as shown in the above mentioned patents.

The chute or race-way comprises the front 70 section 7 and the back section 8 which are adjustably secured together by means of adjusting screws 9. The space 10 between the front and back of the chute constitutes the space in which the buttons 11 are received, 75 and the front 7 of the chute is formed with a groove or kerf 12, which extends from the hopper 3 to the lower end of the chute and in which the shanks or eyes 13 of the buttons are received as they travel down the 80 chute.

The parts thus far described are or may be all as shown in the above mentioned patents and constitute no part of my present invention.

85 There are some shoe buttons made after the manner shown in Fig. 6, that is, that body 11 of the button is formed with a projection or protuberance 14 extending from the under side thereof, said projection 90 or protuberance having the eye or shank 13 extending therefrom. Other shoe buttons have a flat under face as shown in Fig. 4 of the above mentioned patent, No. 1,099,254. Buttons of the type having the flat under 95 face as shown in the above mentioned patent have a larger or longer eye or shank than buttons having the construction shown in Fig. 6 and which are provided with the central protuberance 14. In order that the 100 buttons may be sewed properly to the shoe top or other material it is essential that the eye of the button which is at the lower end of the chute in button-attaching position should project sufficiently beyond the 105 front face of the chute to permit the needle to pass through said eye or shank, and in order that this result may be secured when buttons of the type shown in Fig. 6 are used I propose to make the front section of the 110

chute with the beveled or chamfered edges 16 at the open side of the kerf 12. These beveled or chamfered edges form a counter-sink or groove adapted to receive the projection or protuberance 14 so that the flat edge 18 of the button may rest against the face 19 of the front chute section 7. With this construction at the delivery end of the chute the shorter eye or shank 13 projects 10 sufficiently beyond the front face 20 of the chute so that the needle will enter properly the eye or shank.

The beveled or chamfered edges 16 may extend throughout a greater or less portion 15 of the kerf 12, the important thing being that they exist at the lower or delivery end of the chute so that when the button is in attaching position the shank or eye 13 thereof will project through the front of the 20 chute a sufficient distance to permit the needle to pass therethrough.

In the preferred embodiment of my invention I propose to extend the chamfered edges 16 to the top of the chute and to bevel 25 the edges 16 a progressively decreasing amount from the lower to the upper end of the chute. At the upper end of the chute the beveling or chamfering of the edges is practically nothing, the amount of bevel or 30 chamfer increasing progressively from the top to the bottom of the chute. The purpose of this construction is to avoid any possible interference with the delivery of the buttons to the chute from the hopper 3.

35 The presence of the groove formed by the chamfered edges 16 does not interfere in any way with the use of the chute in attaching buttons having a flat under face as shown in said patent No. 1,099,254, be- 40 cause when flat-faced buttons are used the peripheral portion of the flat-face will rest against the face 19 of the front chute sec-

tion and the button will thus be supported in the same position as if the chute were not provided with the chamfered edges. 45

It will be noted that the race-way is formed with a slight depression 26 at its lower end. This depression is so situated that the button which occupies it will be in button-attaching position, and said recess 50 therefore constitutes a button-positioning recess for the button which is in button-attaching position.

The machine illustrated in Fig. 1 is of the type adapted to sew a button to the shoe 55 top or other material, but my invention is equally applicable to button-attaching machines constructed to attach a button to the material by means of a wire or other attaching element. 60

I claim:

In a machine for attaching buttons each having a central protuberance on its under face, the combination with button-attaching mechanism, of a chute for delivering buttons thereto, said chute comprising spaced front and rear sections between which the buttons are received, the front section having a shank-receiving groove which is provided with a flaring mouth of 65 progressively-increasing width from the entering to the delivery end of the chute, said mouth at the delivery end being of sufficient transverse dimension to receive the protuberance on the button, but of less transverse 70 dimension than the diameter of the button whereby each button at the delivery end will be supported by engagement of the under face of the button outside of said protuberance with the face of the front 75 section.

In testimony whereof I have signed my name to this specification.

CHRISTIAN H. T. HAGELSTEIN.
